[57] CLAIM

The ornamental design for a fruit and produce container, as shown and described.

DESCRIPTION

FIG. 1 is a front upper perspective view of the fruit and produce container of the present invention showing my new design;

FIG. 2 is a rear bottom perspective view thereof;

FIG. 3 is a front upper perspective view with the lid panels disposed in an open configuration; and,

FIG. 4 is an enlarged cutaway view of one of the internal corners of the fruit and produce container of the present invention.

*Fig. 1**Fig. 2**Fig. 3**Fig. 4*
